TOE PROTECTOR

Arthur W. Hauer, Cicero, Ill.

Application April 30, 1934, Serial No. 723,073

5 Claims. (Cl. 36—72)

This invention relates to toe protectors, or guards, for shoes and particularly to rigid toe guards adapted to be removably secured to a shoe over the toe portion thereof.

5 The main objects of this invention are to provide a rigid cap arranged to be secured over the toe portion of a shoe to prevent the same from being crushed as by heavy bodies or falling objects; and to provide such a device having simple 10 means for removably securing the same in position on a shoe.

A specific embodiment of this invention is shown in the accompanying drawing in which:

Figure 1 is a side elevation of the toe protector 15 as applied to a shoe, the shoe being shown in dotted outline.

Fig. 2 is a sectional view as taken on the line 2—2 of Fig. 1.

Fig. 3 is a side elevation of a toe protector showing a modified form of locking means.

Fig. 4 is an enlarged fragmentary sectional view as taken on the line 4—4 of Fig. 3.

In the form shown in Figures 1 and 2 of the drawing, my improved toe protector comprises a 25 metal cap 1 shaped to fit over the toe portion of a shoe 2 and having an open side 1.1 into which the shoe extends. The lower edge of the cap or guard 1 is preferably arranged to rest against the margin of the shoe sole 3 and is provided with 30 an inwardly turned flange 4 arranged to fit into the angular space between the shoe upper and the sole adjacent the seam line where the two are sewed together. By thus engaging the shoe upper at the point where it is turned under and sewed to the shoe sole, the cap or guard 1 is held 35 against vertical movement away from the shoe sole.

The toe guard 1 is applied to the shoe by sliding it over the toe portion of the shoe in a direction 40 parallel to the plane of the shoe sole, the toe portion of the shoe entering the cap through the open side 1.1. Thus the flange 4 which engages the shoe upper is slidably moved into engaging position between the upper and the sole so as to 45 firmly hold the protector or guard 1 on the shoe.

The protector or guard 1 is held in place and locked to the sole by means of a pair of pointed prongs 5 which are disposed on the inner side of the protector cap 1 and pivoted on a horizontal 50 axis so as to be swingable each in a vertical plane. As shown in Figs. 1 and 2, these prongs comprise the ends of a leverage bale 6 disposed on the outside of the protector 1, the ends comprising the prongs 5 being turned at right angles to pass 55 each through an aperture 7 in the side wall of the

guard 1 to the inside of the same where they are again turned at right angles downwardly as shown in Fig. 2. Thus when the bale 6, which is arranged to swing forwardly and downwardly toward the forward tip of the shoe, is thus actuated, the prongs 5 which operate through a small slot or opening 8 in the flange 4 are lifted or swung upwardly so as to be disengaged from the sole 3; and conversely when the bale 6 is swung to a substantially vertical position, the prongs 5 are projected downwardly so as to penetrate into the marginal surface of the sole 3 and thus lock the protector in place.

It may be noted that one of the pivot bearing apertures or holes 7 is elongated horizontally, as shown in Fig. 1, to facilitate assemblage of the bale 6 on the cap 1 when the bale is in its "down" position and pulled forward.

As shown in Fig. 1 the top surface of the protector 1 is formed with a pair of small ribs or 20 ridges 9—9 which provide a means for locking the bale 6 in an upright position, the bale being sprung over the forward ridge so as to be held in the space between the two ridges 9. Thus it will be seen that when the toe protector or cap 1 has been slidably positioned over the toe of a shoe and the prongs 5 projected into the surface of the sole margin by moving the bale 6 to its upright position, the toe protector will be firmly held against both vertical and horizontal movement, so that the protector or guard 1 cannot inadvertently be lost from the shoe.

A modification of the locking means for securing the toe protector 1 against horizontal movement on the shoe is shown in Figs. 3 and 4. In 35 this form the bale has been eliminated, each prong 5' being carried on an arm 10 pivotally secured at 10' on the inner side of the toe protector side walls and having a handle portion 11 projecting through an arcuate aperture 12 in the side of the toe guard, by means of which handle 40 the arm 10 can be shifted so as to swing the prong 5 upwardly away from the sole, or downwardly to penetrate into the sole as the case may be.

The resilient handle 11 is preferably provided with a small aperture 13 arranged to be engaged by projections 14 formed in the side wall of the toe guard 1 so that the arm 10 will be held resiliently in a proper position against inadvertment 50 movement. The handle 11 is bent inwardly against the toe guard so that it must be sprung over the projections 13 when being moved thus assuring that the projections will engage the aperture 12.

55

As shown in Fig. 2 the toe protector 1 is provided with a lining 15, preferably of felt, which is for the purpose of protecting the surface of the shoe from being marred by the protector and 5 to provide a cushion. This lining, however, is optional and is only a preferential detail of construction.

It is understood that in the manufacture of 10 most shoes, the shoe upper is first sewed to a welt (a detail not here shown) and the welt is sewed to the shoe sole; and in such case the flange 4 of the toe guard will engage between the welt and the shoe upper where they are sewed together and the prongs 5 will be projected into 15 the welt when the toe guard is locked in position over the toe portion of the shoe.

The welt feature of the shoe has not been illustrated since it is a well known shoe construction and does not alter the operation or function of 20 the herein-described improved toe guard.

A cam may be used in place of a lever to lock the protector in place.

It is to be understood that some of the details set forth may be altered or omitted without departing from the spirit of the invention as defined by the following claims:

I claim:

1. A toe protector for shoes comprising a rigid cap shaped to fit over and enclose the toe portion 30 of a shoe, an inwardly projecting marginal flange on said cap arranged to engage said shoe, and a shiftable prong mounted on said cap and arranged to be projected into the margin of the shoe sole to lock said cap against shifting thereupon.

2. A toe protector for shoes comprising a rigid cap shaped to fit over and enclose the toe portion

of a shoe, an inwardly projecting marginal flange on said cap arranged to engage said shoe adjacent the line of fastening between the upper and sole thereof, and a shiftable prong mounted on said cap and arranged to be projected into the margin of the shoe sole to lock said cap against shifting thereupon. 5

3. A toe protector for shoes comprising a rigid cap shaped to fit over the toe portion of a shoe, means on said cap arranged to engage the upper 10 of said shoe adjacent the line of fastening between said upper and the shoe sole, and a vertically swingable prong pivotally mounted on said cap and arranged to be projected downwardly 15 into the margin of the shoe sole to lock said cap against shifting thereupon.

4. A toe protector for shoes comprising a substantially rigid cap shaped to fit over the toe portion of a shoe, means on said cap arranged to engage the upper of said shoe adjacent the line 20 of fastening between said upper and the shoe sole, and a bale extending over the top of said cap and having its ends pivoted in apertures in the sides of said cap adjacent its bottom margin, the ends of said bale being bent at right angles 25 on the inside of said cap and said bale being swingable on said cap to project said ends into the marginal surface of said shoe sole.

5. A toe protector for shoes comprising a rigid cap shaped to fit over and enclose the toe portion 30 of a shoe, an inwardly projecting marginal flange on said cap arranged to fit in the corner between the sole and the upper and engage the upper, and means mounted on said cap to engage the margin of the shoe sole to lock said cap on 35 the shoe.

ARTHUR W. HAUER.
